UNITED STATES PATENT OFFICE.

WALDEMAR KOPS, OF NEW YORK, N. Y., ASSIGNOR, BY MESNE ASSIGNMENTS, TO
NEMO CIRCLET COMPANY, INC., A CORPORATION OF NEW YORK.

BRASSIÈRE.

1,415,655.

Specification of Letters Patent. Patented May 9, 1922.

Application filed February 17, 1921. Serial No. 445,642.

To all whom it may concern:

Be it known that I, WALDEMAR KOPS, a citizen of the United States, residing in the borough of Manhattan, city, county, and State of New York, have invented an Improvement in Brassières, of which the following is a specification.

This invention relates to a brassière and more particularly to that type of brassières in which there are included a front member having extensions adapted to pass rearwardly around the body of the wearer with tapes extending therefrom to be continued to the front of the wearer where the same are tied to adjust and secure the front member in position, together with a back member to which there are also extensions adapted to pass forwardly around the body of the wearer and to be connected through suitable means at the front of the body preferably at the waistline to complete the adjustment of the garment and to secure the same in position. In garments of this type, as heretofore constructed, however, it has been customary to employ one set of tapes extending from the front member and adapted to pass around the body and to be secured at the front thereof, and a second set of tapes secured to the extensions of the back member to be passed around the body of the wearer and to be secured at the front portion thereof, preferably at the waist line. The object of the present invention is to so construct a brassière that one set of these tapes is eliminated, causing the set of tapes which is employed to coact with devices connected to one of the members for simultaneously adjusting the same to position with the adjustment of the member to which the tapes are attached.

To this end in carrying out the invention the brassière made in accordance therewith comprises a front member with side extensions and a back member also provided with side extensions, together with a set of tapes connected to the extensions of one member and adapted to coact with devices attached to the extensions of the other member so both members may be simultaneously adjusted and secured in position on the body of the wearer by the use of a single set of tapes as will be hereinafter more particularly described.

In the drawing:

Fig. 1 is a perspective view of a brassière made in accordance with my invention, and

Fig. 2 is an enlarged plan of the garment showing the front member as superimposed upon the back member.

Referring to the drawing, it will be seen that the brassière made in accordance with this invention preferably comprises a front member 10 connected to a back member 11 by suitable shoulder straps 12 and 13 or otherwise. The front member preferably includes side extensions 14 and 15 from which there extend adjusting tapes 16 and 17. The back member 11 is also provided with side extensions 18 and 19 and attached to and extending from the ends of these extensions there are straps 20 and 21. Connected at the otherwise free end of the strap 20 there is a ring 22 and similarly connected to the strap 21 there is a ring 23. Also as illustrated the front member at the lower front central portion thereof is provided with a strap 24 to which is connected a hook 25 for attachment to the corset or other under garment to prevent the front member from working upwardly after being adjusted to the desired position on the body.

As illustrated clearly in Fig. 2 the tape 16 passes through the ring 23 and the tape 17 through the ring 22 so that in the use of the garment, after the same has been placed on the body, the extensions 14 and 15 of the front member are passed rearwardly around the body and the extensions 18 and 19 of the back member passed forwardly around the body to overlie portions of the extensions 14, 15 of the front member and the tape 17 continuing around the waist of the body and through the ring 22 and the tape 16 continuing around the body in the opposite direction and extending through the ring 23; the ends of the tape may then be drawn together simultaneously applying tension to the extensions of the front member to adjust the same in position and in the opposite direction to the rings 22 and 23 to apply tension to the extension of the back member in the opposite direction and may then be tied at the front, preferably at the waist line after this adjustment has been effected to secure the parts of the garment in position.

As herein shown and described, the tapes 16 and 17 are attached to the extensions of the front member and caused to co-operate with the straps and rings connected to the 5 extensions of the back member, although, as will be understood, this construction may be varied without departing from the nature and spirit of my invention. For instance the front member extensions might 10 be caused to overlap instead of underlie the extensions of the back member, in which structure the tapes 16 and 17 would naturally be connected to the back member and the straps 20 and 21 and their rings 22 and 15 23 be connected to the extensions of the front member, when of course the adjustment would be effected at the back of the wearer.

I claim as my invention:

20 1. In a brassière, a front member having portions adapted to extend partially around the waist of the wearer, a back member having portions adapted to extend partially around the waist of the wearer, the said 25 portions of the front and back members being adapted to overlie each other at the sides of the wearer, and tapes connected to the ends of one of the said members and adapted to continue around the waist of 30 the wearer and to be threaded through and to coact with devices associated with the ends of the other member whereby in drawing the tapes and securing the same together the said members are simultaneously 35 adjusted to position on the body of the wearer.

2. In a brassière, a front member, side extensions associated therewith, a back member, side extensions associated therewith, the 40 said extensions being adapted to extend partially around the waist of the wearer and to overlie each other at the side portions of the body, tapes extending from the extensions of the front member and adapted

to pass around the waist of the wearer, and 45 devices connected with the extremities of the extensions of the back member and through which the said tapes are passed after extending around the back of the wearer so as to coact with the back member 50 in such a manner that by drawing the tapes and tying the same together the parts of the garment are simultaneously adjusted and maintained in position on the body of the wearer.

3. In a brassière, a front member, side extensions associated therewith, a back member, side extensions associated therewith, tapes extending from the side extensions of the front member, straps extending from the 60 side extensions of the back member, and rings connected to the said straps and through which the said tapes pass to simultaneously adjust both the front and back member to position and maintain the same 65 in place on the body of the wearer.

4. In a brassière, a front member, side extensions associated therewith, a back member, side extensions associated therewith, shoulder straps connecting the front and 70 back members, a ring connected at the extremity of each of the side extensions of the back member, a tape connected to one side extension of the front member and passing through the ring connected to the opposite 75 side extension of the back member, and a tape connected to the other side extension of the front member and passing through the ring at the extremity of the other side extension of the back member whereby the 80 tapes may be drawn at the front to simultaneously adjust both the front and the back member to position and maintain the same in place on the body of the wearer.

Signed by me this 31st day of January, 85
1921.

WALDEMAR KOPS.
